Patented May 29, 1928.

UNITED STATES PATENT OFFICE.

MONROE C. GRIGGS, OF EXETER, CALIFORNIA.

LADDER.

Application filed June 28, 1927. Serial No. 202,094.

This invention relates to improvements in ladders, the principal object of my invention being to provide a structure of this general character which may be used both as a step ladder and as a straight ladder; the ordinary difference between these two forms being that a step ladder requires a third leg for its support, while a straight ladder is usually longer and its upper end is intended to bear directly against a fixed support which a step ladder will not reach.

My improved ladder combines the advantages of both forms of structure in a single unit, and can be very easily manipulated to set it to serve either purpose.

A further object of the invention is to produce a simple and inexpensive device, and yet one which will be exceedingly effective for the purpose for which it is designed.

These objects I accomplish by means of such structure and relative arrangement of parts as will fully appear by a perusal of the following specification and claims.

In the drawings similar characters of reference indicate corresponding parts in the several views:

Fig. 1 is a rear perspective view of my improved ladder structure as used as a step ladder.

Fig. 2 is a front perspective view of the device as in use as a straight ladder.

Fig. 3 is a fragmentary vertical section of the ladder showing the adjustable leg or bar positioned for use as a straight ladder.

Fig. 4 is a cross section on the line 4—4 of Fig. 3.

Referring now more particularly to the characters of reference on the drawings the ladder comprises vertical side rails 1 extending between and connected to which is a plurality of steps or rungs 2, the rails at the top being surmounted by a relatively heavy cap-step 3.

Projecting rearwardly from and secured to the upper one of the steps 2 centrally of its width between the rails is a rigid loop or stirrup 4 through which is slidable a rigid bar or leg 5 of substantially the same length as the rails. Some distance from the top of the back of the bar carries a wide hook 6 to detachably engage from above the adjacent transversely extending member of the stirrup. When the hook is thus engaged it forms a hinge about which the bar may rock,

the upper end of the bar then riding in a guide groove 7 cut in the lower surface of the cap-step, and the top of the groove then engaging the top of the bar in order to prevent disengagement of the hook from the stirrup. When the leg is disposed at a predetermined and suitable angle to the ladder so that the latter will be properly supported relative to the ground, the forward face of the bar at the top bears against a stop 8 formed at the forward end of the groove, thus preventing further spreading of the leg and avoiding the need of any movement limiting braces or straps therebetween. The ladder may then of course be used for any purpose for which a step ladder is suitable, as will be evident.

When the use of the ladder is not desired the member 5 is merely swung on its hinge connection so as to lie adjacent the back of the ladder.

Secured to the forward face of the bar 5 near the bottom is a downwardly depending angled hook pin 9 which is adapted when the bar is disposed parallel to the rails to enter a centrally located hole 10 provided in certain ones of the steps 2 from the lower one upwardly. In order to thus position and set the bar 5, the latter is moved clear of the groove 7, the hook 9 is disengaged from the stirrup and the bar is slid upwardly until the hook 9 alines with which ever step-hole it is desired to engage said hook with. The bar is then lowered slightly so as to cause the hook to enter the hole. The bar will then project varied distances above the cap-step (depending upon which of the steps 2 is used in engaging the hook) and will bear against the rear edge of said step. The upper end of the bar may then be rested against any fixed surface, as shown in Fig. 2, so that the ladder may then be used where a step ladder is unsuitable, since, as will be evident, such supporting surface may be at a height nearly twice that of the rails 1, or of the ladder proper. At the same time the ladder when folded is very compact and relatively short.

From the foregoing description it will be readily seen that I have produced such a device as substantially fulfills the objects of the invention as set forth herein.

While this specification sets forth in detail the present and preferred construction of the device, still in practice such devia-

tions from such detail may be resorted to as do not form a departure from the spirit of the invention, as defined by the appended claims.

5 Having thus described my invention what I claim as new and useful and desire to secure by Letters Patent is:

1. A ladder comprising spaced side rails and steps therebetween to form a rigid unit, 10 a centrally disposed stirrup projecting rearwardly from an upper step, a bar slidable through and guided by the stirrup for swinging movement thereabout, the top of the bar being adapted to pass under the topmost step of the ladder when said bar is disposed angularly to the side rails, the bar clearing the topmost step when disposed 15 parallel to the side rails, and a downwardly projecting hook on the forward face of the bar near the bottom to detachably engage

orifices provided in the various steps centrally of the width thereof.

2. A ladder comprising spaced side rails and steps therebetween to form a rigid unit, 25 a vertical bar disposed behind the unit centrally of the width thereof and arranged to be moved to occupy positions at an angle to the side rails or parallel thereto and to be capable of upward movement relative to the unit when in the latter position, guide means 30 for the bar on the unit to enable the bar to be swung about said means as an axis to the above named positions, and means between the bar and unit for preventing deflection of the bar both laterally and from a parallel 35 relationship to the side rails after the bar has been initially swung to such parallel position.

In testimony whereof I affix my signature.
MONROE C. GRIGGS.
